Fig. 1

FIG. 2

FIG. 3

FIG. 1 is a front, top and right side perspective view of an organ console, showing my new design.

FIG. 2 is a front perspective view thereof.

FIG. 3 is a fragmentary side elevational view thereof with a part broken away.

The dominant features of my new design are shown in solid lines in the drawings. The conventional manuals, fragmentarily shown, are continuous within the dot-dash lines as indicated. The conventional stop tabs, fragmentarily shown, are continuous within the dot-dash lines as indicated. The side of the console not shown is substantially a mirror image of the side shown. The grille across the bottom front of the organ console, fragmentarily shown, is continuous within the boundaries indicated.

The areas shaded in stippling indicate contrast in appearance.

I claim:

The ornamental design for an organ console, substantially as shown and described.
